US0D1024060S

(12) **United States Design Patent** (10) Patent No.: **US D1,024,060 S**
(45) Date of Patent: ** Apr. 23, 2024

(54) **SMART WATCH**

(71) Applicants: **ZEPP INC.**, Cupertino, CA (US);
ANHUI HUAMI INFORMATION TECHNOLOGY CO., LTD., Hefei (CN)

(72) Inventor: **Wei Po Chao**, Hefei (CN)

(73) Assignees: **Anhui Huami Information Technology Co., Ltd.**, Anhui FTZ (CN); **Zepp, Inc.**, Cupertino, CA (US)

(**) Term: **15 Years**

(21) Appl. No.: **35/516,085**

(22) Filed: **Jan. 6, 2023**

(80) **Hague Agreement Data**

Int. Filing Date: **Jan. 6, 2023**

Int. Reg. No.: **DM/226211**

Int. Reg. Date: **Jan. 6, 2023**

Int. Reg. Pub. Date: **Jan. 27, 2023**

(51) **LOC (14) Cl.** **14-02**

(52) **U.S. Cl.**

USPC **D14/344**

(58) **Field of Classification Search**

USPC ..... D14/138 R, 344, 440; D10/30, 31, 32, D10/38, 70, 128, 132; D11/3; D24/167

CPC G04G 17/00; G04G 17/06; G04G 17/08; G04G 17/083; G04G 17/045; G04G 21/00; G04G 21/02; G04G 21/025; G04G 21/06; G04G 21/08; G04G 99/006; A44C 5/00; A44C 5/0007; A44C 5/0015; A44C 5/0045; A44C 5/0053; A44C 5/2052; A44C 5/2071
